UNITED STATES PATENT OFFICE.

LYMAN R. ROBERTS, OF RUTHERFORD, NEW JERSEY, ASSIGNOR TO UNDERWOOD TYPE-WRITER COMPANY, OF NEW YORK, N. Y., A CORPORATION OF DELAWARE.

AUTOMATIC TYPE-WRITER OPERATOR.

1,182,314.

Specification of Letters Patent.

Patented May 9, 1916.

Application filed December 13, 1913. Serial No. 806,408.

To all whom it may concern:

Be it known that I, LYMAN R. ROBERTS, a citizen of the United States, residing in Rutherford, in the county of Bergen and State of New Jersey, have invented certain new and useful Improvements in Automatic Type-Writer Operators, of which the following is a specification.

This invention relates to an improvement 10 in typewriter operators and more especially to the class in which all of the functions of the typewriter can be taken care of automatically, whereby not only one but a dozen machines can be looked after by a single operator, it being merely necessary that the blank paper be supplied thereto in stacks and the typewritten matter removed as accumulated.

This application is an improvement on 20 my applications, No. 646,975, filed August 31, 1911, and No. 680,586, filed February 29, 1912.

An object of this invention is to produce a machine which will be simple in construction, compact in its arrangement, and with the operating parts secluded as much as possible and retired from an exposed position.

In the present machine the keys are actuated from beneath, leaving them exposed to view and even ready to be operated manually, as the connections between the keys and the operating parts are of such a type that the operating parts will not interfere 35 with the free manual operation of the keys. In fact, all of the parts of the typewriter are connected to the operating mechanism in such a way that if it should be desired, the typewriter can be operated by hand. 40 without disconnecting it from the operator.

The machine is of the general type in which the parts are operated by pneumatic actuators, which are controlled by one or more master members passing over tracker 45 boards. In this case two tracker boards are shown, one for writing the body of the matter, such as a letter, and the other for writing inserts, such as a new name and address for each letter. Of course, the inserted matter may also be placed, if desired, even in the midst of the letter, under the control from the second tracker board. The master members are shown of the perforated type, so that when they pass by their tracker boards, they bring perforations suc-

cessively into register with apertures in the tracker boards in order to admit air to individual controllers, each of which governs the action of a pneumatic actuator. This actuator is connected by mechanical means 60 to the particular part of the typewriter which it is to operate. By this means a successive series of actions of the typewriter may be produced according to any predetermined plan which is governed by the perforations in the master member.

As stated above, in the present case one master member controls the body of the written matter and the other master member controls the inserts. It is therefore essential to 70 shift the control of the operator from one master member to the other. This is controlled by special perforations in each master member, so that they bring into action at proper times, shifting mechanism which enables 75 first one master member to be in ascendancy and then the other. In the present instance, where one master member controls the body of the writing, it is desirable to make the same of an endless sheet, so that it can repeat over and over again by passing continually over the tracker board with interruptions mainly for the purpose of allowing 80 the other master member to control the operation of the machine. The other master 85 member in this case is, in fact, a series of individual master members shown in the form of a series of cards perforated to correspond to different inserts, which, in the present case, are different names and addresses. 90

The paper to be written on is supplied to the machine in packs and picked up sheet by sheet at the proper time under the control of one of the master members, by a 95 pneumo-mechanical mechanism, which drops the sheets one by one to the platen on the typewriter as the carriage reaches the end of its return movement. The sheet so dropped is fed beyond the heading thereof, 100 to a point to receive the first line of typewriting, while the previous sheet, which has been completely written on, is fed out and received in a suitable receptacle.

Among the important improvements in 105 the present case, is the means for rotating the platen when a new sheet is fed thereto as mentioned above, to bring the first line for writing to the printing point and to remove the completely written sheet from 110

the platen. This is accomplished by a special drive for the platen from a motor, whose connection to the motor is normally interrupted and made continuous by a clutch 5 when a proper opening in one of the master members comes into register with an aperture in the corresponding tracker board. When closed the clutch is automatically locked in its closed condition so as to continuously drive the platen any predetermined amount. At the same time that the clutch is closed, a valve is connected to be traversed from the driving mechanism of the platen until it comes into engagement with an adjustable stop, whereby it is opened. The opening of the valve excites a pneumatic actuator, which actuator releases the locking means for the clutch, thereby interrupting the drive to the platen, 10 and also disconnects the valve from the traversing means therefor, so that it can be returned by a spring to its normal position. The adjustment of the stop determines the extent of travel of the valve, and hence, the 15 extent of rotation of the platen, which is proportionate thereto, whereby the platen may be rotated any desired number of line spaces.

The same mechanism which rotates the platen at such special points as the changing 20 from a typewritten sheet to a fresh sheet, also operates the paper-feeding mechanism, so that it will lift the sheet to be dropped to the platen. This is accomplished by a sheet-lifter which normally rests on the pack of sheets and has suction cups engaging 25 with the uppermost sheet. At the proper instant, one of the master members brings an opening therein into register with 30 an aperture in its tracker board, so that this lifter is connected up with the source of suction; then when the clutch mentioned above is connected, a cam will be rotated to shift this sheet-lifter to a raised position, holding 35 up the uppermost sheet, and the sheet-lifter will be locked in this position. Now, when 40 the carriage reaches the end of its return movement, air will be admitted to the sheet-lifter, permitting the sheet raised to drop 45 up to the platen, where it will be fed around by the platen-rotating mechanism. The 50 lock for the lifter will remain in action until some one of the keys of the typewriter is actuated, as it is releasable automatically 55 solely by the universal bar of the typewriting mechanism, which trips it when the master member starts to bring the typewriting mechanism once more into action. That 60 is to say, the first time the universal bar is actuated, it will trip this locking mechanism for the sheet-lifter and permit it to return to a position with its pneumatic suction cups in engagement with the next fresh sheet on the stack.

65 The return of the carriage is obtained by

connecting up a special retrieving mechanism therefor in driven relation with a motor, by means of a normally open clutch. This mechanism is so operated that it locks the clutch in its closed position, the unlocking of which takes place when the carriage is returned its full limit as determined by a margin gage, by a valve located on the margin gage and tripped by the carriage, so as to bring into play a pneumatic actuator which releases the locking means. 75

Other features and advantages will hereinafter appear.

In the accompanying drawings, Figure 1 is a general view in side elevation of the machine as a whole, with parts omitted for the sake of simplicity, and showing, in dotted lines, the path of travel of a completely typewritten sheet in leaving the platen. Fig. 2 is a detail of the manual means for controlling the activity of the machine. Fig. 3 is a skeleton view in side elevation, showing the means for silencing the feed for both tracker boards when the carriage is being returned. Fig. 4 is an enlarged fragmentary view in side elevation, showing parts of the typewriting mechanism with connections of the operating mechanism thereto. Fig. 5 is a detail section through one of the pneumatic actuators 95 and the control therefor. Fig. 6 is a view of the machine as a whole in front elevation, with many parts omitted for the sake of simplicity. Fig. 7 is a horizontal section on the line 7—7 of Fig. 1, showing the general relation of the pneumatic actuators to one of the tracker boards, and also showing details of the platen-rotating mechanism and the sheet-feeding mechanism. Fig. 8 is a rear view in elevation of the sheet-feeding mechanism, and also of the platen-rotating mechanism which is used when the sheet is first fed to the platen to bring the initial line of printing to the printing point, that is, the feeding mechanism which rotates the platen in passing the heading on the sheet to be typewritten and in removing a written sheet from the platen. Fig. 9 is a detail perspective view of the mechanism for controlling the extent of feed or rotation of the platen. Fig. 10 is a view in side elevation, showing the sheet-feeding mechanism. In this view, the sheet-lifter is shown in full lines in engagement with the pile of sheets, and in dotted lines in its 110 position lifting a sheet from the pile ready to drop it to the platen. Fig. 11 is a perspective view of the parts shown in Fig. 10, with the sheet-lifter in its raised position away from the pile of sheets. Fig. 12 115 is an enlarged perspective view, showing the mechanism for receiving the sheet from the sheet-feeding mechanism and directing it to the platen, the sheet-lifter being shown in this case with the sheet withdrawn from 120 125 130

the pile ready to drop it into the receiving mechanism. Fig. 13 is a skeleton perspective view, showing the mechanism for controlling the termination of the return movement of the carriage and also the termination of the extent of drive of the platen in bringing a new sheet to the writing point. Fig. 14 is a top plan view showing a margin gage or stop and its valve control, whereby it governs the extent of return movement of the carriage by disconnecting the driving mechanism for the carriage. Fig. 15 is a detail perspective view of a part of the margin gage shown in Fig. 14. Fig. 16 is a perspective view showing the carriage with the margin gage having a pneumatic control thereon, and the driving mechanism for rotating the platen in bringing a new sheet to the printing point. Fig. 17 is a detail of the valve on the margin gage which controls the extent of travel of the carriage or, in other words, controls the stopping of the drive of the carriage in its return movement. Figs. 18, 19 and 20 are details of the mechanisms for operating the sheet-lifter when the carriage is returned, so that when the carriage reaches the extreme of its return movement, the sheet-lifter will be operated to lift the sheet and drop it on the platen when the platen is properly positioned to receive it. Fig. 21 is a detail view of the platen-rotating and sheet-feeding drive. Fig. 22 is a detail section along the main drive shaft, showing the clutch for connecting up the traversing mechanism of the typewriter carriage. Fig. 23 is an enlarged view in elevation of the lower part of the machine, showing the driving connections from the motor to the various parts, and more especially the carriage-return-driving means. Fig. 24 is a horizontal view in section, on the line 24—24 of Fig. 1, of the lower part of the machine, showing the motor drive and some of the connections to the lower tracker board. Fig. 25 is a vertical section through the master-card feeding and substituting mechanism. Fig. 26 is a detail perspective view of the means for bringing the master-card substituting mechanism into play. Fig. 27 is a plan view of a master card with the perforations corresponding to the address "John Doe, 30 Vesey st., New York, N. Y." Fig. 28 is a diagrammatic plan view of the keyboard of a typewriter. This view taken in connection with Fig. 27 shows the relation of the perforations to the position of the keys. Fig. 29 is a fragmentary perspective view of the master sheet, showing the perforations corresponding to the beginning of a letter, giving the date "Oct. 15/13" and the salutation. Fig. 30 is a skeleton perspective view showing the two trackers and the branch connections of the tubing thereto, whereby either tracker may control much of the actuating mechanism, such as the actuators for the keys, which must be commonly operated under the control of both the trackers. Figs. 31 to 35 inclusive, are detail views showing the mechanisms for shifting from one tracker board to the other, as after writing the address, shifting to the master sheet to control the writing of the body of the letter. These several views show the shifting mechanisms in the several different positions which they will occupy during a continuous operation of the machine.

An operator 1 actuates all of the parts of a typewriter 2 essential to a complete type-writing action.

Considering briefly the parts of the typewriter, which is shown in the present instance to be an Underwood although any other machine might be used, character keys 3 (Fig. 4) operate levers 4 to rock bell cranks 5, so as to swing type-bars 6 up rearwardly against the front side of a platen 7 mounted to rotate on a carriage 8, which travels on ways on the frame of the typewriter, under the control of an escapement mechanism indicated in general at 9. This escapement mechanism includes a rack bar 10, pivotally mounted on the frame of the carriage 8, so as to swing into and out of engagement with a pinion 11 connected to rotate with an escapement wheel 12, which is controlled by a pair of dogs 13 actuated by a universal frame 14, which is operated at the actuation of any of the keys, by heels 15 provided on all of the type-bars. The universal frame 14 is mounted for movement on a swinging frame 16. Particular attention is called to this point, inasmuch as this part is used to release the locking mechanism which holds the sheet-lifter in its elevated position when any key is struck after having fed a new sheet of paper to the typewriter. The frame 16 may be operated also by a space key 17, which forms also a part of the typewriting mechanism, and depresses a lever 18 to thrust up an arm 19 provided on the shift frame 16. The platen 7 has the usual line-space wheel 20 (Fig. 16), which is engaged by the usual line-space mechanism including the line-space lever 21, which may be operated by hand or automatically in the manner to be described.

Having thus briefly described the more essential parts of the typewriter, a more elaborate and detailed description of the operator therefor may be taken up. The automatic operator for the typewriter has its motive source in an electric motor 22 (Fig. 1), which is provided with a shaft 23 having a worm 24 thereon meshing with a worm wheel 25 to drive the same, so as to drive a shaft 26 on which the worm wheel 25 is secured. The shaft 26 is provided with a pair of eccentrics 27 and 28 arranged in

opposite phases on the shaft 26, so as to drive, by means of straps and eccentric rods 29, the two sections 30 and 31 of a bellows vacuum pump. One section will be filling 5 while the other is exhausting, so that a common vacuum chamber 32 therefor will be always under a section so long as the motor 22 is driving. The suction or vacuum chamber 32 has connected thereto, a main pipe 33, 10 which, by virtue of a feeder 34 and various laterals 35, is arranged to connect with the source of suction, the several pneumatic actuators for the different parts of the hereinafter mentioned vacuum chambers 48 of 15 the mechanism.

Considering specifically the operation of one of these pneumatic actuators, which will serve for all as they act substantially alike, it will be seen by reference to Fig. 5, that 20 each actuator consists of a motor 36 in the form of a collapsible bellows, and a controller 37, which is connected to the motor by a pipe 38. Each controller 37 is connected by tubing 39 to either one or both of 25 a pair of trackers or tracker boards 40 (Fig. 1) and 41 (Fig. 25), according to whether the particular actuator to which the controller corresponds is to be controlled in its 30 action by one or both of the trackers and their master members. That is to say, one 35 of the trackers, take, for example, the tracker 40, is used to control the writing of the main portion or body of the matter to be typewritten, and the other, such as the tracker 41, is used to control the writing of the inserts, such as the different names and addresses placed at the top of the several letters.

In the case of the tracker board 40, the 40 master member which controls the same, is shown in the form of an endless perforated sheet 42 (Figs. 1 and 29), which may be passed repeatedly in front of the tracker 40, as the matter which it controls, such as the 45 body of the letter, is to be repeated over and over again in each new sheet of typewriting. In the case of the upper tracker 41, which controls the writing of the inserts, the master member may, in fact, be several 50 different master members shown in the form of individual perforated cards 43, which are successively brought into coöperation with the tracker 41 to successively control the action thereof.

55 It is to be understood at this point that the control of the action of the operator 1 is alternately given over entirely first to one tracker board and then to the other. That is to say, the upper tracker 41 will first control the writing of the address, then the control will be shifted to the lower tracker, when the body of the letter will be written; after which, when a new sheet is placed on the typewriter, the control will again be 60 shifted back to the upper tracker to write a 65

new name and address for the new sheet, and so on.

Going back at this point to the particular structure of each actuator and its controller, when one of the master members brings an 70 opening therein into register with an aperture in its tracker board, the particular controller connected thereto by the tubing 39 will have air admitted in a chamber 44. This chamber is normally under a negative 75 or sub-atmospheric pressure, as it is connected with the source of vacuum. This connection is obtained by having each of the tubes or tubings 39 extend through a common suction or bleed chamber 45 (Figs. 7 80 and 23), connected by a lateral with the feeder 34, the portion of each tube within said bleed chamber 45 being provided with a bleed opening 46^a of sufficient size to gradually exhaust the air from the corresponding 85 chamber 44 in the accordant controller 37, but not fast enough to absorb the air admitted through the alined apertures in the master sheet and the tracker in operation. It is thus evident that when air is admitted 90 to the chamber 44 of any particular controller, it will fill the chamber 44 of the controller, raising a diaphragm 46 which forms the top of the chamber, and carrying with this diaphragm, a valve rod 47, which extends upwardly through an intermediate 95 vacuum chamber 48 into an equalizing chamber 49. The chamber 48 is connected, as mentioned above, to the suction pump by the main pipe 33 and the feeder 34 and the 100 laterals 35. This chamber 48 may be common, if desired, to a bank of controllers 37 or individual to each controller.

When the pressure of air admitted to the chamber 44 raises the diaphragm 46 and the 105 valve rod 47 against the weight of the parts and the negative pressure in the vacuum chamber 48, it also raises a valve 50 secured to the valve rod 47. This valve 50 is duplex and first opens a passage 51, forming a 110 means of communication between the vacuum chamber 48 and the equalizing chamber 49, and then closes a passage 52 between the equalizing chamber 49 and the outside atmosphere. That is to say, the valve 50 is 115 double-ended and operates to alternately close and open the passages 51 and 52. When the valve 50 is raised, it connects the equalizing chamber 49 with the vacuum chamber 48, so that air is withdrawn from 120 the equalizing chamber, and this will continue until the valve 50 closes the passage 52, when the air will not only be sucked out of the equalizing chamber 49, but, through the connecting pipe 38, will also be sucked 125 out of the pneumatic bellows motor 36 forming the active part of the actuator. When the air is thus withdrawn from the interior of an actuator, the outside atmospheric pressure causes the same to collapse, so that any 130

part connected to the moving side 53 thereof will be operated.

When the opening in the master sheet passes out of register with the aperture in the tracker board which causes this action, the air will be cut off from the chamber 44, so that the air remaining therein will be sucked out through the bleed opening 46^a until the pressure on both sides of the dia-

10 phragm 46 is balanced, causing the weight of the parts to drop the valve 50 to a position closing the passage 51 and opening the passage 52. The bellows motor 36 being cut off from the suction and opened up to

15 atmospheric pressure, will expand and return to its normal condition with the aid of a spreading spring, not shown.

In the case of the actuators which operate the various keys of the typewriter, each one is provided with an arm 54 (Figs. 1, 4 and 6), which is connected by a link 55 to one arm of a bell crank 56. The other arm 57 of each bell crank 56 is provided with a pin 58, which overlies a hook 59 on a link 60 pivoted to the corresponding key of the typewriting mechanism. That is to say, each key is provided with a link 60 having hook 59 underlying one of the pins 58 on one of the bell cranks 56. The arms 57 of the bell cranks are of various lengths and arranged in echelon, so as to avoid one another and coöperate with their corresponding links 60.

It will be seen that any of the keys of the typewriting mechanism, whether the character keys 3, the space key 17, the shift keys, tabulating key, or any other key, may be operated by the corresponding one of the actuators 36.

40 It will further be seen that the connections are such that the keys may be operated manually without disturbing the actuating mechanism. That is to say, any of the keys may be depressed when their hooks 59 will merely move downwardly away from the pins 58, without disturbing the bell cranks 56. This permits the typewriting mechanism to be operated by hand as well as by the pneumatic operator.

50 The actuators 36 may be arranged in tiers and banks, as illustrated in Fig. 7, with the individuals in the several rows stretched with respect to the individuals in the other rows, so as to avoid interference one with the others. Of course it will be understood that all of the actuators for all of the keys of the typewriter are connected to both trackers, as it is essential to control them for writing both the address and the body of the letter.

Having considered how the pneumatic actuator is constructed and acts, we may now go on to the description of the feeding mechanism for the master members, which controls the action of all of the actuators, and

how the shift is made from control by one to control by the other at the proper times.

The master sheet 42, which controls the writing of the main part or body of the typewritten matter, such as the body of the letter, passes over a supporting feeding roller 61 (Fig. 13) and is warped across the face of the tracker 40 by means of an idle roller 62 (Fig. 23). The supporting roller 61 is provided with a gear 63, which may be driven at times by a gear 64 secured on a shaft 65, on which is also secured a roller 66. When the master sheet 42 and its tracker 40 are in control, the feeding roller 66 is dropped down to bind the master sheet 42 between its surface and the surface of the supporting roller 61. Under these conditions, the gear 64 will also mesh with the gear 63, so as to drive the same; hence the master sheet will be fed in the direction of the arrow shown in Fig. 1, past the tracker 40, bringing the several perforations therein successively into register with corresponding apertures in the tracker 40.

To drive the shaft 65 and thus the rollers 61 and 66, there is provided on the shaft 65, a gear 67 (Fig. 13), which meshes with a pinion 68 (Fig. 23) secured to a shaft 69 carrying a pulley 70, which is driven by an endless belt 71 from a pulley 72. The pulley 72 is secured to a shaft 73 on which is also secured a friction disk 74 driven by a friction roller 75 bearing against one surface on the disk 74. The friction roller 75 is secured to a shaft 76 driven by a pair of meshing bevel gears 77 and 78, from the cross shaft 26, which, as mentioned above, is driven from the motor 22.

The feeding mechanism for the upper master member is also driven from the shaft 73. For this purpose, there is provided on this shaft, a second pulley 79 (Fig. 7), which is connected, by means of an endless belt 80, to drive a pulley 81 on a shaft 82. The shaft 82 also has secured thereon a pinion 83 meshing with the gear 84 secured on a shaft 85. Also secured on the shaft 85, there is provided a pinion 86, which when lowered is arranged to drive a pinion 87 secured on a shaft 88. The shaft 88 has secured thereon a sectional feeding roller 89, the sections of which extend through openings in a guide 90 to engage the upper master card 43 which happens to be in action (Fig. 7). A similarly sectioned feeding roller 91 (Figs. 7 and 25) passes through openings in the guide 90 and coöperates with the opposite side of the master card 43 in action, so that when the shaft 89 is being driven, the card will be fed down by the coöperation of both the feeding rollers 89 and 91, they being connected to rotate in unison by pinions 92 and 93, secured, respectively, to the feeding roller 89 and the feeding roller 91. A bearing roller 94 corrugated so as to avoid obstructing the

openings in the master card 43, holds the master card against the tracker 41, in order to obtain an airtight fit therebetween. This bearing roller is floatingly supported by a frame 95 pivotally mounted at 96, and engaged by a spring 97^a which holds the bearing roller 94 to its work. As noted above, however, both master members, that is, the master card and the master sheet, are not in control at the same time. To regulate this change in control, the drive is completed to the feeding mechanism for one master member and interrupted to the feeding mechanism for the other master member, and vice versa. To accomplish this, the shaft 65 for the master sheet 42 is floatingly mounted by a frame including arms 97 (Figs. 13 and 23) pivotally supported on the shaft 69, so as to swing relatively thereto without disturbing the driving connection to the shaft 69. Likewise, the shaft 85 for the master sheet 43 is floatingly mounted by means of a frame including one or more arms 98 pivoted on the shaft 82, so as to swing relatively there- to without interrupting the connection between the gears 83 and 84. One of the arms 97 is provided with a camming socket 99, in which may rest a camming roller 100 secured to the lower end of a shifting lever 101. This shifting lever is pivoted, intermediate its ends, as at 102 (Figs. 3 and 25), and is provided at its upper end with a bearing roller 103 coöperating with a cam socket 104 in one of the upper arms 98.

It will be seen that when the lever 101 is in the position shown in Figs. 4 and 13, the roller-bearing end of the arm 97 will be lowered, so as to permit the roller 66 to drive the master sheet 42, and also permit it to drive the supporting roller 61 through engagement of the gear 64 with the gear 63. This same position of the lever 101, however, as shown in Fig. 4, causes the bearing roller 103 to rest on the dwell portion above the cam socket 104 and thereby hold the gear 86 out of mesh with the gear 87, so that the drive to the feeding rollers 89, 91, is interrupted. On the other hand, when the lever 101 is shifted to the Fig. 25 position, the master card 43 will be in control as the gear 86 is dropped into mesh with the gear 87, completing the drive to the feeding rollers 89, 91, while the shaft 65 and the roller 66 are raised, interrupting the drive between the gear 64 and the gear 63.

In order to manipulate the shifting lever 101, a pair of pneumatic actuators 105 and 106 are provided (Figs. 31 to 35 inclusive,) which are adapted to shift the lever 101 in opposite directions. The actuator 105, which controls the bringing into play of the feeding mechanism for the master sheet 42, is controlled by a perforation in the particular master card 43 in action; while the actuator 106, which controls the bringing

into play of the feeding mechanism for the master card 43 is controlled by a perforation in the master sheet 42. In other words, one master member controls the bringing into play of the other master member. As the actuators 105 and 106 are of the type described above and shown in Fig. 5, it is not necessary to re-describe them at this point. Sufficient to say that when the actuator 105 is brought into control by an aperture in the master card 43, it will assume the Fig. 31 condition, whereby a link 107 will, by virtue of a hook or shoulder 108 thereon, draw the lever 101 to the Fig. 31 position, by engagement with a rod or lug 109 on the lever 101, the latter being yieldingly held in this position by a spring detent 101^a, Fig. 4.

Now, when the master sheet 42 has finished its period of control, having completely written the body of a letter, after a new work-sheet has been supplied to the typewriter, then a perforation in the said master sheet 42 comes into register with a corresponding aperture in its tracker 40, so as to cause the pneumatic actuator 106 to collapse its bellows motor. This will bring about a condition in the actuator 106, such as shown in Fig. 32, whereby a thrust link 110 will be plunged forwardly, first causing a cam nose 111 thereon to engage a pin 112 on the link 107, disengaging the shoulder 108 from the lug 109, so as to free the lever 101 from the actuator 105 and its link 107. A further movement of the thrust link 110 causes a shoulder 113 thereon to engage the lug 109 and force the lever 101 from the Fig. 31 position to its Fig. 33 position, whereby the cam roller 103 will drop into the socket 104, permitting the arm 98 to lower the gear 86 into mesh with the gear 87, thereby completing the drive to the feeding rollers 89, 91, so as to feed the master card 43 into position past its tracker 41. At the same time, the lower roller 100 and the lever 101 rock, by a camming action, the arm 97, so as to withdraw the gear 64 from its meshing position with the gear 63, thereby interrupting the drive to the master sheet 42. When the master card thus started into control has been fed to the end of its capacity for control, and has finished writing of a name and address, a perforation therein comes into register with a corresponding aperture in its tracker 41, causing the actuator 105 to come into action. When this takes place, the actuator pulls the link 107 from the Fig. 33 position to the Fig. 34 position, when the pin 112 engages the end of the nose 111, camming the latter upward, so as to disengage the shoulder 113 from the lug 109. A further movement of the link 107 under the pull of the actuator 105, causes the shoulder 108 on this link to engage the

lug 109 and shift the lever 101 from the Fig. 33 position to the Fig. 35 position, or back to its original Fig. 31 position; the bellows motor of the actuator 106 in the 5 meantime expanding to the condition shown in Fig. 31 ready for a subsequent action. Under these conditions the feed to the master card 43 will be interrupted and the driving connection to the feeding mechanism 10 nism of the master sheet 42 completed, so that the control is once more shifted from the master card to the master sheet, enabling the writing of the body of the letter beneath the name and address already written. 15

It is advisable at times to throw out the feeding mechanisms for both the master card and the master sheet, as when it is necessary to stop the machine or when 20 the carriage is being traversed, or the platen rotated. In the last two cases, it would be inadvisable to have keys struck when the work-sheet is in motion. To accomplish this manually, as in stopping the operation 25 of the machine, there is provided a throw-out button 114 (Figs. 2, 3 and 13), which, when the machine is in action, has a groove 115 in register with a shifting bar 116, pivoted at 117. When, however, it is desired 30 to disconnect the drives for both the feeding mechanisms, the manual button is rotated from the Fig. 3 position to the Fig. 2 position. The bar 116 is then shifted about its pivot 117 to draw on a link 118, 35 so as to rock a bell crank 119. This bell crank is provided with an arm 120, having an offset 121 (Fig. 13), which underlies the arm 97 supporting the shaft 65 and the roller 66. The arm 120 of the bell crank 40 119 is also connected by a link 122, to an arm 123 also having an offset underlying the shifting frame or arm 98, which shifts the gear 86 of the driving mechanism for the master card-feeding mechanism.

45 It will thus be seen that both the arms 97 and 98 will be swung with their gearing-bearing end raised, so as to simultaneously interrupt the drive to both the feeding mechanisms. That is to say, when the button 114 is rotated to the Fig. 2 position, it simultaneously interrupts the drive for both master members, so that the machine is silenced. This action is also effected, as will be explained presently, when the carriage is returning to begin a new line and 55 when the platen is being rotated to either position the new work-sheet on the platen or to discharge a completed letter from the platen.

60 After one master card has completed its work and shifted the control to the master sheet, then it must be removed from an effective position and a fresh card put in its place, so that a new name and address can 65 be written on the next work-sheet fed to the

platen. To accomplish this, the master cards 43 are stacked vertically in a holder or receptacle 124 (Figs. 1, 4 and 25). The face of the receptacle is open and the cards are kept with the foremost one adjacent the 70 front of the receptacle 124, by a back plate 125, which is provided with supporting rollers 126 so that it may travel evenly on ways or rails 127. The back plate is advanced by a frame 128, which is connected to 75 the back plate by links 129. The frame 128 is pivoted at 130 and normally urged to advance the back plate 125 by one or more springs 131. It will thus be seen that when cards are removed one by one from the receptacle 124, the stack will be advanced, always bringing the foremost card ready to be removed from the receptacle and passed down to the feeding mechanism including 80 the feeding rollers 89 and 91. 85

To effect this substitution of a card from the receptacle 124 for a card in action, there is provided a card-substitutor 132, which includes a card-catcher 133 having a slightly projecting ledge 134 of just sufficient magnitude to overlie the top edge of the foremost master card 43. The card-substitutor 132 is normally located in its uppermost position and so held by one or more springs 135. The card-substitutor 132 is guided for vertical 90 movement by a plurality of rollers 136 engaging rails 137 provided on the receptacle 124. It is also held in a justified position so as to advance the cards in a rectilinear line, by means of a plurality of pinions 138 secured to a shaft 139, which rotates in bearings on the card-substitutor 132, but the pinions 138 on which engage in a pair of fixed racks 140 secured to the card receptacle 124. 95

100 For the purpose of depressing the card-substitutor 132, there is provided a pair of continuously rotating gears 141 (Fig. 7) secured to a shaft 142, which is provided with a bevel gear 143 (Fig. 7) meshing with a bevel gear 144 on the shaft 76, which, as 105 mentioned above, is driven from the shaft 26 and thus from the motor 22. So long as the motor is in action, the shaft 142 and the gears 141 will be continuously rotating. There is, however, normally no connection 110 between the gears 141 and the card-substitutor 132. There is provided, though, a pair of racks 145 (Figs. 25 and 26) pivotally mounted at 146 on the card-substitutor 132, normally out of engagement with the gears 120 141 but capable of being forced into engagement with the gears 141. The racks 145 have arms 147, which are connected by links 148 to arms 149 pivoted at 150. The spring or 125 springs 135 previously mentioned, are connected to the arms 149 and exert their tension to hold the card-substitutor 132 in its raised position through the intermediary of the links 148 and the arms 147. It will be seen that these springs 135 also hold the 130

racks 145 out of engagement with the pinions 141.

When it is desired to replace a master card 43 which has finished its function of writing a name and address, by a fresh master card taken from the receptacle 124, an opening in the master card just in action in line with an opening which controls the shift of control from the master card to the master sheet, will come into register with a corresponding aperture in the tracker 41, so as to incite to action, in the usual way, a pneumatic actuator 151. The bellows motor of this actuator 151 collapses, drawing on a link 152, which swings an arm 153 to rock a shaft 154. The shaft 154 carries one or more arms 155 to engage pins 156 on shifting levers 157 (Figs. 25 and 26). Each of these shifting levers 157 carries a bearing roller 158, which engages the corresponding rack 145 on the rear side thereof. It will thus be seen that the bringing into play of the pneumatic actuator 151 shifts both the racks 145 into engagement with the constantly-rotating gears 141, so that the racks 145 will be depressed, carrying down with them the card-substitutor 132, which carries with it the foremost master card 43. The shifting levers 157 are locked in their actuated position by a latch 159, which is rocked by each lever 157 itself through the intermediary of a spring 160, to bring a toe 161 on each latch under a pin 162 on each lever 157.

As the card-substitutor 132 moves downwardly against the tension of the spring or springs 135, a lever 163, which has a pin-and-slot connection 164 with the arm 149, is rocked, so that a cam toe 165 on the lever 163 will come into engagement with a lower roller 166 on a swinging frame 167, which latter supports the sectional feeding roller 91. A spring 168 normally holds the feeding roller 91 to its work against the card 43 between the rollers 89 and 91. When, however, the card-substitutor is in action, the roller 91 is moved from the roller 89, so as to permit the new card coming down between them, to be easily moved. That is to say, the lever 163 spreads the rollers 89 and 91 against the tension of the spring 168, to permit the new card to be readily slipped between them. The new card in passing downwardly through the guide 90, will force out the previously active master card 43 through the open-bottom end of the guide, into a suitable receptacle placed beneath the same. When the card-substitutor has completed its work, the new card will be located with the initial blank portion thereof in opposition to the openings in the tracker 41.

As the card-substitutor completes its downward movement, it automatically disconnects itself from the driving gears 141. To do this, the racks 145 are provided with pins 169, which engage the latches 159 and

trip them, permitting the springs 160 to restore the shifting levers 157 and the latches 159 to their normal positions as shown in Fig. 26. The springs 135 immediately withdraw the racks 145 from engagement with the driving gears 141 and return the card-substitutor to its raised position, when the back plate 125 will advance slightly, bringing a fresh master card 43 beneath the overhanging ledge 134 on the card-catcher 133. A fresh card may be substituted at any time for the one in action, manually if desired, by means of a handle 170 provided on the shaft 154 and located outside the casing on the machine.

While writing any matter with the typewriter, it is essential to return the typewriter carriage and to line-space the platen at the end of each line so as to enable the beginning of a new line. To enable the automatic operator to perform this function, there is provided on the shaft 26, which, as stated above, is driven from the motor 22, a sprocket 171 (Figs. 22 and 23). This sprocket is not fixed on the shaft 26, but is connectible thereto, so as to be driven thereby, and thus drive an open stretch of sprocket chain 172, which is flexibly connected, as by one or more springs 173, to a draw-band 174 (Figs. 6, 12 and 16). This draw-band forms with the chain, a complete endless traversing member, which passes over one or more guiding rollers 175 on the operator frame and also over guiding rollers 176, 177 on the typewriting machine frame. These last rollers may be offset considerably from the typewriter frame, by brackets 178, to give the necessary reach in traversing the typewriter carriage 8.

The draw-band 174 has secured thereto a connector 179, which is provided with a hook 180 to engage the line-space lever 21, so as to space the platen as well as return the carriage when the draw-band is traversed in a clockwise direction, as in Fig. 12. The backward movement of the draw-band 174 relatively to the carriage 8, is limited by a shoulder 181 formed by a bend in the connector 179, which shoulder engages a shoulder 182 provided on a guide 183, through which guide the band 174 extends and which is secured on the typewriter carriage 8. The normal spring 21^a (Fig. 16) of the line-space mechanism of course acts when the traction on the draw-band 174 is released, to return the connector 179 and the parts joined thereto to the positions shown in Fig. 12.

In order to connect the sprocket wheel 171 in driven relation with the shaft 26, there is provided a clutch element 184 (Figs. 22 and 23), which is secured to the sprocket 171 in any suitable manner, such as that shown in Fig. 22. A second clutch element 185 is splined on the shaft 26 and shiftable against the tension of a spring 187, which normally holds it out of engagement with the clutch 130

element 184, into engagement therewith, so as to complete the driving connection between the sprocket 171 and the shaft 26.

To move the clutch element 185 against the 5 tension of the spring 187, there is provided a clutch shifter 188, pivoted at 189, and limited in its movement, owing to the impulse of the spring 187, by an adjustable stop 190. The clutch shifter 188 is operable by a pneumatic actuator 191 under the control of either the master card or the master sheet according to which is in action. That is to say, when the end of a line of typewriting is reached, a carriage-return perforation in the 15 master member in control, will come into opposition with an aperture in the corresponding tracker, exciting the pneumatic actuator 191 to operation in the usual way, so that the bellows motor thereof will collapse, drawing on a link 192 (Figs. 13 and 23), which extends through a guide 193 in the shifter 188, and is provided with a notch 194 having teeth on either side thereof, so that the link 192 can settle over a pin 195 provided on the shifter 188. Thus, when the bellows motor of the actuator collapses, it draws on the link 192 to rock the shifter 188 to the right (Fig. 23), so as to close the clutch comprising the elements 184 and 185 and 30 thus connects the sprocket 171 in driven relation with the shaft 26, thereby enabling the return of the carriage and the line-spacing of the platen by means of the draw-band 174.

35 It will be noted in passing that the movement of this shifter 188, to cause a return movement of the carriage, also disconnects the drive to both the feeding mechanisms of the master control sets, so that whichever 40 one is in action will be silenced until the carriage is completely returned, thus preventing any typewriting action of the keys while the work-sheet is moving. This is accomplished by the pin 195, which is extended 45 to engage the bar 116 (Figs. 3 and 13), whereby the link 118 will be drawn on to lift both sets of the gear-bearing frames or arms 97 and 98. Of course this stopping of the master sheet in action leaves the 50 perforation which caused the collapsing of the bellows motor of the actuator 191, in register with the aperture in the tracker, thereby maintaining this actuator in action until the carriage has been completely returned. 55 That is to say, the drive from the shaft 26 and thus from the motor, is maintained until the carriage reaches the limit of its return movement. The limit of this return movement is determined by a margin gage 196, 60 which is adjustably mounted on the typewriter frame.

As the carriage 8 of the typewriter approaches the end of its return movement, a 65 trip 197 comes into engagement with an adjustable stop 198 (Figs. 12, 14, 16 and 17),

which is secured to a valve 199 pivotally mounted on the margin gage 196. This valve is normally held in its closed position by a spring 200, so as to prevent air leaking into a controlling tap 201. When, however, 70 the carriage reaches the limit of its movement, it rocks the valve 199, admitting air to the tap 201 and thus to tubing 202 connected thereto. This tubing is connected to the control of a pneumatic actuator 203, so 75 that the latter will come into action at this time. When the pneumatic motor of this pneumatic actuator 203 is collapsed, it forces a plunger 204 (Fig. 23) forwardly, so that the latter, through the intermediary of a pin 80 205 carried thereby, engages a cam surface 206 on the link 192 and raises the same against the tension of a spring 207, so as to withdraw the notch 194 of the link 192 from engagement with the pin 195. When the 85 link 192 is thus disconnected from the shifter 188, the spring 187 is free to act, forcing the clutch element 185 away from the clutch element 184, and disconnecting the sprocket 171 from driven relation with the 90 shaft 26. The return of the shifting lever 188 also permits the return of the bar 116, and thus allows the particular feeding mechanism which was in action before the carriage started to return, to come into action 95 once more, so as to drive its master member to advance the carriage-return perforation and bring the next perforation into register with its proper aperture in the accordant tracker board.

100 In Fig. 22, it will be seen that the sprocket 171 is mounted loosely on a sleeve 208 mounted loosely on the shaft 26 between collars 209 and 210. The sprocket 171 is merely frictionally connected to a disk 211 bearing the clutch element 184, so that it may have a certain amount of slippage relatively to the clutch, to take up any jar in suddenly connecting the clutch in driven relation with the shaft 26, and also to prevent 110 the breakage of any of the parts in case the carriage reaches the limit of its return stroke before the clutch element 185 is disconnected from the clutch element 184. To obtain this lost motion and yet positive connection, the 115 sprocket 171 is clamped between the disk 211 and a disk 212, with a pair of friction washers 213 and 214, one on either side of the sprocket 171, the sleeve 208 being screw-threaded at its ends to coöperate with corresponding screw-threads on the disk 211 and the disk 212.

120 After a work-sheet has been completely written, as with the full name and address and body of the letter, this sheet must be removed from the platen and a fresh one put on in place thereof. To eject the finished sheet from the platen, the platen could be rotated by repeated operations of the line-space lever by the carriage-return mecha- 125 130

nism. However, special means for rotating the platen is also provided which can accomplish the same purpose somewhat more quickly. For this purpose, the platen axle 215 extends beyond the frame of the carriage where it is provided with a sprocket 216 (Fig. 12) driven by a sprocket chain 217, which in turn is driven by a sprocket 218 on a shaft 219. The shaft 219 is provided with a gear 220 meshing with a barrel pinion 221 on a shaft 222, which is mounted to rotate on a fixed portion of the frame. The shaft 219 is mounted on the carriage so that it travels therewith and causes its gear 220 to mesh with the barrel pinion 221 when the carriage is at the end of its return movement. The barrel pinion is of considerable length so as to allow for the drive of the platen therefrom at a variety of positions of the carriage 8.

To drive the barrel pinion 221, the shaft 222 is provided with a bevel gear 223 (Fig. 8), which is driven by a bevel gear 224 on a shaft 225. This shaft 225 also has a bevel gear 226 driven by a bevel gear 227 loosely mounted on a shaft 228. The bevel gear 227, however, is normally connected in driven relation with the shaft 228 by a one-way clutch element 229 thereon meshing with a corresponding clutch element 230 splined on the shaft 228 (Fig. 21). A spring 231 normally holds the clutch element 230 in mesh with the clutch element 229, so that rotation of the shaft 228 in the direction of the arrow shown in Fig. 21, will be transmitted to the clutch element 229 and thus to the bevel gear 227. If, however, the shaft 228 rotates in a counter-direction, the clutch element 230 will slip idly past the clutch element 229, without disturbing the gear 227 and the train of gearing to the platen. The shaft 228 is normally silent but has a sprocket wheel 232 loosely mounted thereon; by means of which it may be driven. This sprocket wheel is driven by a chain-and-sprocket connection 233 (Figs. 4 and 7), from the constantly-rotating shaft 142 (Fig. 25), which, as explained above, is driven from the motor 22.

To drive the shaft 228 from the sprocket wheel 232, there is provided on the sprocket wheel 232, a clutch element 234, into engagement with which may be shifted a clutch element 235 splined on the shaft 228 (Figs. 8 and 13). The clutch element 235 is provided with an annular groove, into which extend pins on a clutch-shifter 236, which latter is normally held by a spring 237, in a position corresponding to the disengagement of the clutch element 235 with respect to the clutch element 234. The shifter 236, however, is provided with a follower roller 238, engaged by a cam 239 on a lever 240 pivoted at 241.

When it is necessary to rotate the platen,

as in removing a completed sheet therefrom, a perforation in the master sheet comes into register with an aperture in the tracker and excites to action a pneumatic actuator 242, so that the bellows motor thereof collapses to thrust forwardly a plunger 243. This plunger engages in a crotch 244 provided on the lever 240 and has a shoulder 245 to engage a part, forming with the lever 240 the crotch, so as to shift the lever 240 and cause the cam 239 to manipulate the shifter 236 against the tension of the spring 237 in order to bring about an engagement of the clutch element 235 with the clutch element 234, thereby connecting the shaft 228 in driven relation with the sprocket wheel 232 which is constantly rotating.

While the platen is rotating, it is essential to stop the movement of the master member in control, so the bar 116 is actuated to interrupt the drive to both master-member feeding mechanisms in the manner described above. For this purpose, the shifter 240, when actuated, also pulls on a link 250 to swing an arm 251 secured to a rock shaft 252, which is also provided with an arm 253 having an extension 254 engaging this bar 116, to rock the same to its disconnecting position shown in Fig. 2.

The plunger 243 is provided with a notch 246 which catches over a latch 247 on one face of the actuator 242, so that the bellows motor of the actuator is held in its collapsed position until the plunger 243 is raised out of engagement with the latch 247. This latter movement is permissible, inasmuch as the plunger 243 is pivotally mounted at 248 on a lug 249 carried by the moving side of the bellows motor of the actuator 242. By this arrangement, the clutch element 235 is held in engagement with the clutch element 234, so long as the plunger 243 is in locking engagement with the latch 247. Under these conditions, the platen will be rotated through the train of gearing continuously, until the plunger 243 is raised, permitting the unclutching of the continuously-rotating sprocket 232 from the shaft 228. To accomplish this disconnection automatically, use is made of the same actuator 203 which tripped the carriage-return actuating mechanism at the completion of the return of the carriage. For this purpose, a branch 255 (Fig. 13) of the tubing 202 which leads to the control of the actuator 203, is connected to a valve 256, which is normally closed but openable when the desired extent of rotation of the platen has been accomplished. When this valve is opened, it admits air in the usual way to the controller of the actuator 203, so that the bellows motor collapses and shoots forwardly the thrust-link 204, which, in addition to the pin 205, carries a second pin 257, arranged to engage one arm 258 (Figs. 13 and 23) of a bell crank lever, having a sec-

this equalizing chamber 49 is under a suction, owing to the raising of the valve 50, when air is admitted to the lower compartment 44, it will also cause the air to be 5 sucked out of the pipe 288. The pipe 288 is connected to the bottom end of a rigid tube 289 (Figs. 4, 8, 10, 11 and 20), which tube extends up through a sleeve or standard 290 and is provided at its upwardly-projecting end, with a flexible rubber tube 291 (Fig. 10), which forms a means of communication with the interior of the bail 283, and is connected thereto along the pivot reach 292 thereof, which extends through the 15 pivot brackets 284. It will be seen by this means that when the proper perforation in the master sheet 42 comes into register with the accordant aperture in the tracker 40, air will be sucked out of the bail 283, and 20 hence cause a suction from the cups 285, so that the uppermost sheet of the stack supported by the receptacle 275 will be drawn to the cups 285, as indicated in full lines in Fig. 10. Before this sheet, however, can 25 be deposited on the platen 7, it must be lifted clear of the lower supporting ledge of the receptacle 275. To accomplish this, use is made of the driving mechanism which rotates the platen, to remove the sheet previously written from the platen and to properly position the new sheet on the platen. The shaft 228 (Figs. 13, 20 and 21) which, as mentioned above, is rotated to drive the 30 platen 7 a number of line spaces at a time, is provided at one end with a cam 293, which is shown in the form of a cylinder having on the end face thereof, an annular cam surface 294. The cam surface starts at a point and gradually slopes to a maximum 35 height where it dips abruptly to the starting point. The cam 293 always when silent, occupies the same position, which may be termed the "home position", with the starting point of the cam surface 294 in contact 40 with a follower roller 295 on an arm 296 (Fig. 20), which is fixed on the rigid tube 289, for which the sleeve 290 forms bearings in which the tube may oscillate. As the shaft 228 rotates, it rotates the cam 293, so 45 as to gradually swing the arm 296 and thus gradually rock the rigid tube 289. This rocking motion is transferred to an arm 297, also secured to the rigid tube 289 at its upper end. The arm 297 is arranged to 50 transmit its motion to a rocking frame 298, which is pivotally mounted on the rod 280. The arm 297 is provided with a pair of spaced pins 299, which engage on opposite sides of a rail 300 provided on the swinging 55 frame 298, whereby the arm 297 may rock the frame 298 (Figs. 10 and 11). The swinging frame 298 imparts its movement, by means of an arm 301, to the bail of the sheet-lifter 283, with which it engages by 60 means of a pair of spaced pins 302. The 65

rocking of the arm 296 by the cam 293 thus takes place when the shaft 228 rotates, whereby the sheet-lifter 283 is moved to the full-line position shown in Fig. 11, from the full-line position shown in Fig. 10, where it holds the uppermost sheet on the stack in a suspended position ready to drop it to the platen 7.

The parts are held in this position until the sheet has been dropped by cutting off the suction to the sheet-lifter 283 and admitting air thereto. To hold the sheet-lifter in its elevated position, a latch 303 (Fig. 20) is drawn by a spring 304 to engage a shoulder 305 of the arm 296 and hold it in a position corresponding to the raised position of the sheet-lifter 283, shown in dotted lines in Fig. 10. The suction is cut off from the sheet-lifter 283, so as to drop the sheet suspended to the platen, by the master sheet 42 traveling along to bring the opening therein out of register with the aperture in the tracker. After the work-sheet has been dropped from the lifter 283, the latch 303 may be released, permitting the 90 return of the sheet-lifter 283 to a position with the cups 285 in engagement with the next work-sheet at the top of the stack in the receptacle 275. In order that the latch 303 may be released, it is secured to a 95 rock shaft 306, which also has secured thereon an angular tripping arm 307, the end of which lies in the path of movement of the supporting frame 16 (Figs. 4 and 20) for the universal frame 14 of the typewriter. It will be evident, then, as soon as any key of the typewriting mechanism is actuated by the operative, that the frame 16 will be shifted and thus swing the arm 307 to release the latch 303, permitting the 100 105 arm 296 to swing to its normal position shown in Fig. 20, the cam 293 having, in the meantime, returned to its home position with the dip in register with the follower roller 295.

To bring the cam 293 to its home position after each actuation, there is loosely mounted on the shaft 228 (Figs. 19 and 21), a spool or drum 308, which has secured there-to one end of a coil spring 309, the other end 115 of which is secured to a fixed portion of the frame 310.

As the shaft 228 rotates in the manner above mentioned, this motion will be transmitted to the drum 308 by means of a pair 120 of friction disks 311 and 312, the former of which is secured to the shaft 228 and the latter of which is yieldingly pressed into engagement with one side of the spool 308 by a spring 313 abutting against a collar 125 314. It will be seen that the spring 313 normally tends to clamp the spool 308 between the clutch disks 311 and 312, so that the spool will tend to rotate the shaft 228, until the spring 309 is completely wound 130

ond arm 259 provided with a pin 260 underlying the plunger 243.

It will thus be seen that when the valve 256 is opened, it will raise the plunger 243, removing the notch 246 out of engagement with the latch 247, and removing the shoulder 245 out of engagement with the crotch 244, permitting the shifter 236 to return under the propulsion of the spring 237, to its disconnecting position, so that the shaft 228 will once more be silent, while the sprocket wheel 232 rotates idly. To open the valve 256, it is given a traveling movement coincident with the rotary movement 15 of the platen and corresponding in extent to the extent of rotation of the platen desired. When the valve 256 completes its desired travel, it comes into engagement with a stop 261, which opens the valve and causes an 20 operation of the actuator 203 as mentioned above. To traverse the valve 256, it is mounted on a carriage 262, which slides on ways or guide rods 263 of a rocking frame 264.

25 When the clutch element 235 is connected up to the clutch element 234 to drive the shaft 228, a pin 265 on the lever 240 engages an arm 266 on the rocking frame 264 to swing the same about its pivot against the tension of a spring 266^a and thereby bring a tooth or segment of a nut 267 (Figs. 7 and 9) into engagement with a bodily stationary but rotating screw 268 secured to the shaft 228 (Fig. 21).

30 35 It will thus be seen that so long as the shaft 228 is rotated to drive the platen, the screw 268 will be rotating to feed the carriage 262 carrying the valve 256 along on the ways 263, until a up. Then any further rotation of the shaft 228 will merely produce a slippage between the faces of the disks 311 and 312 and the heads of the spool 308. The strength of this friction clutch connection may be varied by adjusting the collar 314, which has a screw-threaded connection with the shaft 228.

It will therefore be seen that when the shaft 228 is disconnected from the source of power by the opening of the clutch comprising the elements 234, 235, it will be free to rotate and will be rotated by the spring 309, tending to unwind itself. The extent of this rotation is determined by a spring-pressed locating dog 315, which is pivotally connected at 316 with any part secured to the shaft 228, as, for example, the screw 268. This locating dog 315 is provided with a cam face 317 on one side so that when the shaft 228 rotates in the direction of the arrow in Fig. 18, which direction corresponds to the driving of the platen and the rotating of the cam 293 to raise the sheet-lifter 283, it will slip idly by an obstructing or locking rail 318. When, however, the shaft 228 rotates in a counter-clockwise direction (Fig. 18) under the impulse of the coil spring 309, the opposite abrupt face 319 of the dog 315 will come into engagement with the rail 318, preventing further motion of the shaft 228. The dog 315 is so positioned relatively to the shaft 228 and the cam 293, that when it brings the shaft 228 to a stop, it will always bring the dip of the cam surface 294 into register with the follower 295, so that the arm 296 will be free to return to the position shown in Fig. 20. It will be seen that this action will be positive no matter how much the shaft 228 has been rotated and no matter where it stops in its rotation, as the dog will always bring it up hard at the same point on its return motion.

The new work-sheet dropped to the platen is guided thereto so that it will come with the bottom edge in even register with the bight of the platen. To do this, there is mounted on the carriage 8 (Fig. 12), a sheet-guide 320. This guide may include a pair of chutes 321 and 322 having open sides facing each other and having their fronts and rears sloping downwardly toward each other, so as to come quite close together near the bottom, whereby the sheet will be accurately directed to the bight of the platen. The rear of the chutes 321 and 322 may extend some little distance beyond the front part thereof and contact with the paper shelf surrounding the platen, so as to prevent a swinging movement of the guide as a whole.

The chutes 321 and 322 may be adjustably mounted by means of brackets 323 on a rail 324, so that they can be brought closely to-

gether to accommodate small widths of paper, or stretched away from each other to accommodate wide sheets. The brackets 323 may be locked in any adjustable position along the rail 324 by set-screws 325. The rail 324 has connected thereto, by means of uprights 326, a cross-bar 327, which forms a support for a deflector 328. This deflector engages the top edge of the work sheet as it comes from the platen and swings it toward the front of the typewriting machine, so that as the platen rotates to free itself from the work-sheet after the typewritten matter has been completely written thereon, the sheet will shoot forwardly as indicated in Fig. 1, 80 into a receptacle or basket placed in front of the typewriter. Where the chutes 321 and 322 are spread somewhat widely from each other, the sheet coming thereto might bulge at the middle. To prevent this and 85 properly guide the sheet, there is provided a looped deflector 329 located midway of the chutes 321 and 322, and supported by the cross-bar 327.

As has been mentioned above, the limit of travel of the carriage can be varied so that the position of the stops on its return motion may vary. Inasmuch as the fresh sheet is fed to the carriage when it has reached the limit of its return movement, it is necessary 95 to have the guide 320 come to a point where it will receive the sheet directly from the lifter 283. If the variation in the stopping point of the carriage on its return motion is very great, the difference can be accommodated by bodily adjusting the receptacle 275 which holds the stack of fresh sheets. To enable this adjustment, the sleeve 290 (Figs. 8 and 20) supports dovetailed grooved ways 330 in which extends a correspondingly 100 formed rail 331 mounted on the back of the receptacle 275. The rail 331 may be slid in the ways 330 to any position desired, whereby the receptacle 275 will be correspondingly located. When so adjusted, the receptacle 110 and the rail 331 may be locked by set-screws 332.

It will be noted that the engagement of the lever 297 with the swinging frame 298, by means of the pins 299 and the rail 300, 115 permits of this relative movement without disturbing the capacity of the lever 297, to rock the suction lifter 283 through the intermediary of the swinging frame 298. That is to say, the operative connection to the lifter 283 is not disturbed no matter what the position of the receptacle 275 along its support.

If the machine were to be stopped by the hand button 114 when a carriage-return perforation in either master member was in register with its aperture in the corresponding tracker board, then when the machine is started up again a false carriage return might take place. To avoid this possibility, 120

the bar 116 (Figs. 1, 3 and 23) is provided with an extension 333 having a hook 334 to engage the inclined end of the link 192. The hook 334 moves with the bar 116 when the latter is cammed to the position shown in Fig. 2 by the button 114, so that the link 192 will be raised clear of the pin 195 on the shifting lever 188. Thus, if air should be admitted to the actuator 191, the latter would operate without shifting the lever 188, so that the carriage-return mechanism would not be brought into play. After the mechanism started in action, the perforation in the master sheet would naturally pass away from its actuator, so that the actuator 191 would resume its normal condition. The action of the actuator 191 would, of course, take place, if it happened at all, immediately before the link 192 has had time to drop into engagement with the pin 195.

In considering the operation of the device, it will be assumed that a letter has been completely written on a work-sheet on the platen and we are about to repeat this letter with a new name and address. The master sheet 42 (Figs. 1 and 29) is in control and the feeding mechanism therefor in operation, while the feeding mechanism for the master card is silent and a blank or solid portion of the master card in place is opposite to the apertures in the tracker 41. As the master sheet 42 is fed past its tracker 40, it brings a perforation into register with a corresponding aperture in the tracker 40, which controls the operation of the pneumatic actuator 191, whereby the clutch-shifting lever 188 will be operated to bring the clutch element 185 into engagement with the clutch element 184, so as to enable a carriage-return movement. This is to insure the carriage being at the end of its return movement in a position to receive a new work-sheet from the sheet-feeding mechanism.

When the carriage-return mechanism comes into play it automatically raises the gear 64 out of mesh with the gear 63 through the intermediary of the bar 116, the link 118 and the arm 120 (Figs. 3 and 13), so that the drive to the master sheet is silenced. When, however, the carriage reaches the end of its return movement, the trip thereon engages the stop 198 and opens the valve 199, so as to excite to action the pneumatic actuator 203, whereby the link 192 will be tripped to permit the unclutching of the sprocket wheel 171 from the shaft 26, thereby interrupting the drive to the carriage-return mechanism. This will permit the bar 116 to return to its normal position, thereby permitting the gear 64 to drop into mesh with the gear 63, continuing the feed of the master sheet. The master sheet will thus be moved along to bring two new perforations into play, one corresponding to the rotation of the platen so as to remove

the work-sheet already on the platen, and the other corresponding to the picking up of a fresh sheet of paper by the sheet lifter 283. The first of these perforations excites the actuator 242 to action, so that it thrusts 70 forwardly the plunger 243 to rock the lever 240, which actuates the clutch-shifter 236 against the tension of the spring 237, to connect the shaft 228 in driven relation with the continuously-rotating sprocket 232. The 75 shaft 228 on being driven, rotates, through the connecting gearing, the platen 7 any predetermined amount, so as to remove, or at least partially remove, the completely 80 written work-sheet from the platen, to deposit it in the basket or receptacle in front of the typewriter. The extent of this rotation is determined by the distance traveled by the valve 256 before it comes into engagement with the stop or trip 261, which 85 has been previously adjusted for a rotation of the platen corresponding to any desired number of line spaces. The opening of the valve 256 excites the same actuator 203 to 90 action, which was excited to action at the end of the carriage return, so that the driving connection to the feeding mechanism for the master sheet, which was also interrupted at the starting of the platen into rotation, will be once more completed. 95

As stated above, a second aperture was brought into play at the same time as that controlling the rotation of the platen. This, 100 excited the pneumatic control 287, so that it raised the valve therein to open up communication between the pipe 288 and the source of suction, whereby the sheet-lifter 283 and the suction cups 285 were enabled to cause the uppermost sheet of the stack in the receptacle 275 to adhere to the sheet-lifter 283. After this has occurred and as the shaft 228 starts in rotation, the cam 293 will be rotated to swing, through the interconnecting mechanism, the sheet-lifter 283, 105 to its raised position shown in dotted lines 110 in Fig. 10, ready to drop the fresh work-sheet to the platen. The sheet-lifter 283 is locked in this position by the latch 303 until such subsequent time as any of the keys of the typewriter are actuated. 115

As stated above, the feed to the master sheet is interrupted while the platen is being rotated through the rotation of the shaft 228. Hence, the perforation which caused the suction in the sheet-lifter 283, stops in 120 register with its aperture and remains there until the rotation of the platen has ceased and until the sheet-lifter is raised to the dotted-line position shown in Fig. 10.

When these acts have been accomplished 125 and the rotation of the shaft 228 ceases, the pneumatic actuator 203 not only interrupts the drive to the shaft 228 but also permits the feeding mechanism of the master sheet 42 to come once more into action thereby 130

feeding the two perforations which were in register with their corresponding apertures, to pass by the same. This, in addition to silencing the actuator which connected up 5 the platen in driven relation with the source of power, also silences the control 287, so that the valve thereof cuts off communication between the pipe 288 and the source of suction, connecting the same with the outside 10 atmosphere. When this occurs, the suction will be relieved in the sheet-lifter 283, so that the same is free to drop the suspended sheet into the guide 320 and thus to a position with the bottom edge in register 15 with the bight of the platen.

As the master sheet feeds along, it brings a second platen-rotating perforation into register with its aperture, so that the shaft 228 is once more rotated to finish the 20 charge of the previously written work-sheet if it has not already been entirely fed from the platen, and advance the new work-sheet around the platen 7, to bring the desired line to be written on to the printing point. 25 The valve 256 once more silences the drive to the platen 7 and enables the further feeding of the master sheet 42.

While the shaft 228 was rotating, it tensioned the spring 309 (Fig. 19), so that as 30 soon as the shaft 228 was disconnected from the source of drive, it was rotated in a counter-direction by the spring 309, through the friction clutch which connects the spool 308 with the shaft 228, so that the positioning 35 dog 315 is enabled to stop the shaft 228 at a definite point corresponding to the location of the dip in the cam surface 294 in register with the follower 295. This enables the return of the sheet-lifter 283 and operating 40 mechanism therefor to a normal position when subsequently released from the hold of the latch 303 at the first operation of any key of the typewriting mechanism 2.

As the master sheet 42 is now fed on, it 45 brings the desired number of tabulating perforations in succession into register with the corresponding aperture in the tracker 40, so that the tabulating key shown in Fig. 28 will be operated a corresponding number of times 50 in succession. This will space the carriage 8 with the aid of the tabulating stops on the back of the carriage, which have been previously located, to bring the point on the work-sheet where it is desired to strike the 55 first letter of the date, to the printing point of the typewriter. As the master sheet feeds on, it will bring a "shift on" perforation into register with its aperture which causes the actuation of a quasi-permanent case-shift key; so as to lift the platen to write upper-case 60 characters and hold it there. The next perforation coming into play is the one which operates the "o" key, so that the capital "o" (O) will be struck. It will be noted in passing that the striking of this letter causes the

corresponding type-bar to shift the universal bar 14 of the typewriting machine, so that the supporting frame 16 thereof will be rocked, hitting the arm 307, whereby the latch 303 will be moved from engagement 70 with the arm 296, permitting the return of this arm and the sheet-lifter 283 actuated thereby to their normal positions. A further feed of the master sheet brings a perforation into register with its aperture, 75 which will cause the operation of the temporary shift key, whereby the permanent shift key will be released in the usual manner to once more permit the writing of lower-case characters. This action is continued until the date "Oct. 15/13", as illustrated in Fig. 29, is written. A carriage-return perforation will then come into play, causing the return of the carriage to its starting position. A further feed of the 80 master sheet brings a "control-change" perforation into register with its aperture, so that the pneumatic actuator 106 (Fig. 31) is brought into play to silence the master-sheet control and incite to action the card-control. This first releases the link 107 and then forces over the lever 101 from the Fig. 85 90 position to the Fig. 32 position, whereby the driving mechanism for the feeding rollers to the master sheet 42, will be disconnected. That is to say, the gear 64 will be lifted out of mesh with the gear 63, while the driving mechanism for the card-feeding mechanism will be brought into play; or, in other words, the card-feeding rollers 89, 91 95 100 will be started into action. The master card in place, which we will assume is the one shown in Fig. 27, now starts down past its tracker 41. This card will be placed in the mechanism in the position upside down from 105 that shown in Fig. 27, as the feed is downward. The first perforation coming into play will be the "shift on" perforation, that is the one which actuates the permanent shift key, and then the letter "J" perforation 110 followed by the "shift off" perforation or the one which operates the temporary shift key that releases the permanent shift key, and so on, until the name "John Doe" is written. The carriage-return perforation 115 then comes into play, which automatically causes not only the return of the carriage to its starting point but also the line-spacing of the platen, whose line-space lever 21 is operated by the carriage-return draw-band 120 174, through the intermediary of the connector 179. The tabulating perforation next comes into action, so as to strike the tabulating key once to space for the beginning of the address "30 Vesey St." This, then, is 125 written by the successive perforations coming into play at proper intervals.

The carriage is once more returned and the work-sheet spaced, when the tabulating key will be struck twice under the control of 130

two successive tabulating perforations, so as to indent a little farther for "New York, N. Y." This, likewise, is written by the successive passage of the several perforations past the corresponding apertures in the tracker 41. After this line has been written the carriage is once more returned and the master card fed on subsequently thereto. Two perforations now come into play at 10 the same time, one controlling the shifting from control by the master card to control by the master sheet, and the other governing the exchange of the card in action for a new card. That is to say, it governs the operation 15 of the card-substitutor 132. The first of these two perforations causes an operation of the pneumatic actuator 105, which draws on the link 107 (Fig. 34), to first cam up the thrust link 110 to its disengaged 20 position, and then by it itself engaging the lug 109, rock the lever 101 to the position shown in Figs. 31 and 35, which corresponds to the disconnection of the drive to the card-feeding mechanism and the connection of 25 the drive to the master-sheet-feeding mechanism. While the master sheet is in control, the card-substitutor will be acting as started by the perforation coming into play at the same time that the one which shifted the 30 control to the master-sheet, so that a new card will be brought down by the mechanism shown in Fig. 25, including the card-substitutor 132, so as to force out the card which has finished its action, and bring in 35 place thereof, a new card corresponding to a new name and address. The rollers 89 and 91 will be opened up as explained above, to admit of the insertion of this new card and the card-substitutor will be returned 40 automatically as explained above, after having finished its work. Meanwhile, the master sheet 42 continues its action, writing the body of the letter commencing "Dear Sir".

After the body of the letter has been 45 finished, the master sheet, which is endless, once more brings the perforations around, which control the removal of the written work-sheet and the supplying of a new work-sheet to the platen. This action is 50 repeated over and over again, the master sheet alternating in control with the master cards, a new master card being substituted for each operation of the master sheet, so that any number of letters may be written 55 having substantially the same subject matter with different names and addresses.

Of course, a change may be made from the master sheet to the master card, and vice versa, at any point in the writing of the 60 letter. For example, the date may be put at the bottom of the letter, or the name of the person to whom the letter is directed, or other matter, might be inserted in the midst of the subject matter of the letter, 65 so as to make the same appear somewhat

more personal. To accomplish these objects, it is merely necessary to place the "control change" perforations at the proper points.

Variations may be resorted to within the scope of the invention, and portions of the 70 improvements may be used without others.

Having thus described my invention, I claim:

1. The combination with a typewriting mechanism including keys, of a series of 75 links, one individual to each of said keys and depending therefrom, a series of bell cranks, one individual to each of said links for operating said keys, said bell cranks and said links having a one-way effective connection whereby said bell cranks may operate said links to actuate said keys, and, further, whereby said keys may be actuated independently of the movement of said bell cranks, and individual actuators for each 80 of said bell cranks.

2. The combination with a typewriting mechanism including keys, of a series of 90 links, one individual to each of said keys and depending therefrom, a series of bell cranks, one individual to each of said links for operating said keys, said bell cranks and said links having a one-way effective connection whereby said bell cranks may operate said links to actuate said keys, and, further, whereby said keys may be actuated independently of the movement of said bell cranks, and individual actuators for each 95 of said bell cranks, said bell cranks having their pivots grouped in echelon and having 100 arms extending one beyond the other, the connections of said links with said arms being arranged in groups in echelon to avoid one another.

3. The combination with a typewriting 105 mechanism including a series of keys, of a series of links depending from said keys, one individual to each of said keys, a series of bell cranks for drawing on said links to 110 actuate said keys, there being one bell crank for each of said links, and means for actuating said bell cranks individually, said bell cranks having their pivots arranged in substantially the same plane and each comprising an arm, and an L-shaped arm forming 115 a T-connection with the first arm, so as to avoid the pivots of the other bell cranks and form a point of connection to said links at the arc of greatest throw with least angular movement.

4. The combination with a typewriting mechanism including a series of keys, of links dependent from said keys, there being one link individual to each of said keys, and a series of bell cranks for operating said 125 links, said bell cranks having their pivots arranged in substantially the same plane and having arms extending horizontally on one side of the plane of the pivots, with projections extending upwardly to points of at 130

tachment with said links, so as to bring the points of connection of said bell cranks with said links almost in the plane of said pivots, whereby the pull on said links will be more ⁵ nearly vertical.

5. The combination with a typewriting mechanism including a key, of a link depending from said key, a hook on said link, a bell crank having a pin extending over ¹⁰ said hook, a link for rocking said bell crank, and a pneumatic actuator for actuating said link.

6. The combination with a typewriting mechanism including a traveling carriage ¹⁵ and type actions, of automatic actuators for operating said type actions, an actuator for controlling a traveling movement of said carriage, a master control set having a master member feeding to control successive actions of said actuators, means for concomitantly causing the traveling movement of said carriage and interrupting the feeding movement of said master member, and a pneumatic actuator controlled from said carriage ²⁰ for concomitantly interrupting the movement thereof and continuing the feeding movement of said master member.

7. The combination with a typewriting mechanism including a traveling carriage, ²⁵ of an automatic operator for said typewriting mechanism including carriage-traversing means, shifting mechanism for controlling the action of said carriage-traversing means, silencing means for said automatic operator, and means operated by said silencing means for disconnecting said shifting mechanism to prevent a false action of said carriage-traversing means when said automatic operator is started into action from a ³⁰ silent condition.

8. The combination with a typewriting mechanism including a traveling carriage, ³⁵ of an automatic operator for said typewriting mechanism including carriage-traversing means, shifting mechanism for said traversing means, an actuator for operating said shifting mechanism, a link connecting said actuator with said shifting mechanism, means for disconnecting said link to silence ⁴⁰ said carriage-traversing means, silencing means for stopping the action of said automatic operator, and a connection for said silencing means for disconnecting said link from said shifting mechanism to prevent a ⁴⁵ false action of said carriage-traversing means when said automatic operator is started into action after having been silenced.

9. The combination with an automatic operator, of a plurality of master control sets ⁵⁰ for governing the action of said operator, only one of said control sets dominating the action of said operator at one time, a shifting member for determining the ⁵⁵ dominating control set, and a plurality

of actuators, one corresponding to each control set, for shifting said member to bring the corresponding control set into action, each actuator being positively connectible to said shifting member and acting, ⁷⁰ while being connected thereto, to positively disconnect the previously connected actuator.

10. The combination with an automatic operator, of a plurality of master control ⁷⁵ sets for governing the action of said operator, only one of said control sets dominating the action of said operator at one time, a shifting member for determining the dominating control set, a plurality of actuators, ⁸⁰ one corresponding to each control set, for shifting said member to bring the corresponding control set into action, a link connected to one of said actuators for operating said shifting member in one direction, a link ⁸⁵ connected to another of said actuators for operating said shifting member in the opposite direction, and coöoperating parts on said links acting the one to disengage the other from said member, and vice versa, in shifting ⁹⁰ said member in opposite directions.

11. The combination with an automatic operator, of a plurality of master control sets for governing the action of said operator, only one of said control sets dominating ⁹⁵ the action of said operator at one time, a shifting member for determining the dominating control set, a plurality of actuators, one corresponding to each control set, for shifting said member to bring the corresponding control set into action, a link for shifting said member in one direction, and a link for shifting said member in the opposite direction, said member having a lug to be engaged alternately by each of said links, ¹⁰⁰ one of said links having a nose to engage a pin on the other of said links, so as to disconnect said pin-bearing link from said lug when said nose-bearing link is actuated, and said pin engaging said nose when said pin-bearing link is actuated, to disengage said ¹⁰⁵ nose-bearing link from said lug.

12. The combination with an automatic operator, of a pair of control sets for governing the action of said automatic operator, ¹¹⁵ said control sets alternately dominating the action of said operator, a shifting member for governing the control set in domination, an actuator for shifting said member in one direction, an actuator ¹²⁰ for shifting said member in the opposite direction, a thrust link connected to one of said actuators, a draw-link connected to the other of said actuators, a lug on said member, a shoulder on each of said links to engage said ¹²⁵ lug to shift said member in opposite directions, a cam-nose on one of said links, and a pin on the other of said links, said cam-nose and said pin coöperating to alternately disengage one or the other of said links ¹³⁰.

from said lug according to which link happens to be in engagement with the lug, and according to which link is operated by its actuator.

13. The combination with a typewriting mechanism including a traveling carriage, of an automatic operator for said typewriting mechanism including a carriage-traversing means, a plurality of control sets for alternately dominating the action of said automatic operator, means for locking both of said control sets out of action when said carriage-traversing means is in action, and a pneumatic actuator controlled from said carriage for concomitantly bringing the control set previously dominating the action of said operator into play and stopping the action of said carriage-traversing means.

14. The combination with a platen, of normally silent driving means for rotating said platen, a master member having its general character interrupted at a point to control the bringing into play of said driving means, means for maintaining said point in action while said driving means is in action, and automatic means brought into play at the excitation of said driving means to action for silencing said driving means after a predetermined rotation of said platen and for enabling the passage of said point into inaction.

15. The combination with a platen, of normally silent driving means for said platen, a master member for bringing said driving means into play to rotate said platen many line spaces, said master member normally traveling, means for silencing the travel of said master member when said platen is being rotated by said driving means, and means for starting said master member into motion when said platen ceases its rotation.

16. The combination with a platen, of driving means for rotating said platen, a master member for controlling the bringing into play of said driving means, feeding means for said master member, said feeding means and said driving means alternating in action, and automatic means for silencing said driving means after a predetermined rotation of said platen and enabling the bringing into play of said feeding means.

17. The combination with a platen, of driving means for rotating said platen, a pneumatic actuator for controlling said driving means, a perforated master member for controlling said actuator, a tracker, feeding mechanism for bringing apertures in said master member into register with said tracker, said master member having an aperture controlling the bringing into play of said actuator, means operated by said actuator for silencing said feeding mechanism when said last-mentioned aperture comes into register with said tracker, so as to maintain said last-mentioned aperture in

register with said tracker, and automatic means for disconnecting said driving means after a predetermined rotation of said platen by disconnecting said actuator from said driving means, and for enabling the continuation of the feeding of said master member to bring said last-mentioned aperture out of register with the tracker at the silencing of the drive to said platen.

18. The combination with a platen, of driving means for rotating said platen, an actuator for governing the rotation of said platen by said driving means, a plurality of control sets alternating in domination, any one of which may govern the action of said actuator, automatic means for locking all control sets out of action when said driving means for said platen is in action, and automatic means for silencing said driving means after a predetermined rotation of said platen for bringing the particular control set which was in domination at the starting of said platen in rotation, once more into action.

19. The combination with a platen, of a normally interrupted train of gearing for driving said platen, means for completing said train of gearing, including a lever, an actuator, a plunger operated by said actuator to shift said lever, a master control set for governing the action of said actuator, means for silencing said control set operated from said actuator, and an actuator brought into play at a predetermined rotation of said platen for disengaging said plunger from said lever and rendering inactive said silencing means so as to enable once more the bringing into play of said control set.

20. The combination with a traveling carriage, of a platen rotatably mounted on said carriage, traversing means for said carriage, driving means for rotating said platen, a master control set for governing the action of said traversing means and the action of said driving means, silencing means for said master control set brought into play either at the operation of said traversing means or the operation of said driving means, so that said master control set will be silenced during a traveling movement of said carriage, or a rotating movement of said platen, and an actuator controlled at the end of the traveling movement of said platen to bring into play said master control set.

21. The combination with a traveling carriage, of a platen rotatably mounted on said carriage, traversing means for said carriage, driving means for rotating said platen, and an actuator controlled alternately from said carriage and from said driving means for said platen, for silencing said traversing means or said driving means, according to which is in action, after a predetermined movement of one or the other.

22. The combination with a traveling carriage, of a platen rotatably mounted on said carriage, traversing means for said carriage, driving means for rotating said platen, an actuator for alternately silencing said traversing means or said driving means according to which is in action, a valve controlled from said carriage for controlling said actuator, and a valve controlled from said driving means for controlling said actuator.
23. The combination with a traveling carriage, of a platen rotatably mounted on said carriage, traversing means for said carriage, driving means for rotating said platen, an actuator for bringing said traversing means into play, an actuator for bringing said driving means into play, a pair of master control sets for alternatively controlling said actuators, means for silencing both said master control sets at either an action of said traversing means or an action of said driving means, so that said master control sets will be ineffective during either a traveling movement of said carriage or a rotating movement of said platen, and an actuator controlled from said carriage and said driving means for silencing either said traversing means or said driving means according to which is in action, and for bringing once more into play the particular control set which was in domination before the starting into action of said traversing means or said driving means.
24. The combination with a platen, of line-spacing mechanism for said platen, driving means for rotating said platen independently of said line-spacing mechanism, a sheet-feeder for supplying fresh work-sheets to said platen, means for actuating said sheet-feeder to supply an individual sheet to said platen, means for actuating said driving means to rotate said platen before and after the actuation of said sheet-feeder, so as to remove the old work-sheet from said platen and to position a new work-sheet on said platen, and master-sheet controlled means for governing the operation of said line-spacing mechanism and both of said actuating means.
25. The combination with a platen, of a perforated master member controlling the movements of said platen, and driving mechanism for enabling a single perforation of said master member to control a many-line-space rotary movement of said platen.
26. The combination with a platen, of a master control set for governing rotary movements of said platen and including a master member, spacing mechanism enabling a single perforation in said master member to control a line-space movement of said platen, and driving mechanism enabling a single perforation in said master member to control a many-line-space movement of said platen.
27. The combination with a platen, of a sheet-feeding mechanism for supplying work-sheets to said platen, driving means for rotating said platen varying amounts, actuating means for said sheet-feeding mechanism, operated from said driving means, and localizing means for returning said actuating means to a definite condition irrespective of the extent of movement of said driving means.
28. The combination with a typewriting mechanism including a traveling carriage, a platen rotatably mounted on said carriage, a series of type actions including keys, and a universal frame operated at the actuation of any of said keys, of a sheet-feeding mechanism for supplying work-sheets to said platen, means for actuating said sheet-feeding mechanism, locking means for maintaining said sheet-feeding mechanism in its actuated condition, releasing means for said locking means operated from said universal frame upon the actuation of a key subsequently to an action of said sheet-feeding mechanism, and master-sheet mechanism for controlling the operation both of said keys and of said sheet-feeding mechanism.
29. The combination with a typewriting mechanism including a traveling carriage, a platen rotatably mounted on said carriage, a series of type actions including keys, and a universal frame operated at the actuation of any of said keys, of sheet-feeding mechanism for supplying work-sheets to said platen, actuating means for said sheet-feeding mechanism including an arm, a cam for rocking said arm, locking means engaging said arm to hold said arm and said sheet-feeding mechanism in their actuated condition after having been operated by said cam, releasing means operated by said universal frame to unlock said arm and said sheet-feeding mechanism at the initial action of any key subsequently to an action of said sheet-feeding mechanism, and master-sheet mechanism for controlling the operation both of said keys and of said sheet-feeding mechanism.
30. The combination with a traveling typewriter carriage, of a platen rotatably mounted on said carriage, means for returning said carriage to a definite starting point, pneumatic means for determining the end of a return movement of said carriage to said definite starting point, sheet-feeding mechanism extraneous to said carriage, controlled to feed a fresh work-sheet to said carriage at the end of a return movement of said carriage, and a master control set for governing the operation of said returning means, said pneumatic means and said sheet-feeding mechanism.
31. The combination with a traveling carriage, of a platen rotatably mounted on said carriage, sheet-feeding mechanism ex-

traneous to said carriage for supplying fresh work-sheets to said platen, traversing means for returning said carriage, pneumatic means for determining the limit of the return movement of said carriage, and controlling mechanism for concomitantly effecting a return movement of said carriage and actuating said sheet-feeding mechanism to supply a fresh work-sheet to said platen as said carriage reaches the end of its return movement.

32. The combination with a traveling carriage, of traversing means for effecting a traveling movement of said carriage, pneumatic actuating means for governing the action of said traversing means, master control sets for governing the action of said pneumatic actuating means, and pneumatic actuating means independent of said master control sets for determining the extent of traveling movement carried on by said traversing means.

33. The combination with a platen, of driving mechanism for rotating said platen many line spaces, pneumatic actuating means for governing the action of said driving mechanism, a master control set for bringing said pneumatic actuating means into play, and pneumatic actuating means independent of said master control set for governing the extent of rotation of said platen by said driving mechanism.

34. The combination, with a typewriting mechanism, including a traveling paper-carrier, and key-actuated types arranged to strike thereagainst; of a set of actuators for said types; a master control set for governing the action of said actuators; an actuator controlled from said master control set for starting a return movement of said paper-carrier; and an actuator controlled from said paper-carrier for ending the return movement of said paper-carrier.

35. The combination, with a platen, of driving means for rotating said platen; an actuator for controlling said driving means; a master member for controlling said actuator; feeding means for said master member; an actuator for controlling said feeding means, said feeding means and said driving means alternating in action; and automatic means controlled by the second-named actuator for silencing said driving means after a predetermined rotation of said platen and enabling the bringing into play of said feeding means.

36. The combination, with a platen; of driving means for rotating said platen, said driving means including a normally-open clutch; a master member for controlling the closing of said clutch; feeding means for said master member, said feeding means and said driving means alternating in action; and automatic means enabling the opening of said clutch after a predetermined rota-

tion of said platen and also enabling the bringing into play of said feeding means.

37. The combination, with a platen; of normally-inactive driving means for rotating said platen; a master member for controlling the bringing into action of said driving means; feeding means for said master member, said feeding means and said driving means alternating in action; and automatic means for rendering said driving means inactive after a predetermined rotation of said platen and enabling the bringing into play of said feeding means.

38. The combination, with a platen; of driving means for rotating said platen; a member for controlling the connection and disconnection of said driving means; an actuator for said controlling member to effect such connection; a master member for controlling said actuator; feeding means for said master member, said feeding means and said driving means alternating in action; an actuator for controlling said feeding means; and automatic means controlled by the second-named actuator for operating said controlling member to disconnect said driving means, and enabling the bringing into play of said feeding means.

39. The combination, with a platen; of a train for driving said platen, including a normally-ineffective controlling member; a shifter for said controlling member; an actuator for operating said shifter to render said controlling member effective; a master member for controlling said actuator; feeding means for said master member, said feeding means and said driving train alternating in action; silencing means for said feeding means connected to be operated by said shifter; and automatic means for returning said controlling member to ineffective condition after a predetermined rotation of said platen, and enabling the bringing into play of said feeding means.

40. The combination, with a platen; of a perforated master member controlling the movements of said platen; driving mechanism enabling a single perforation of said master member to control a many-line-space rotary movement of said platen, said mechanism comprising a normally-interrupted driving train leading to said platen, and shifting means for completing said train; and automatic means for again interrupting said train at the completion of such rotary movement.

41. The combination, with a platen, and a carriage therefor; of driving mechanism for causing a many-line-space rotary movement of the platen; means independent of said driving mechanism for effecting a single line-space rotary movement of said platen; carriage-traversing mechanism connected to operate said single-line-space means; and a perforated master member for

controlling both said driving mechanism and said single-line-space means.

42. The combination, with a platen; of a sheet-feeding mechanism for supplying work-sheets to said platen; driving means for rotating said platen varying amounts; actuating means for said sheet-feeding mechanism, operated from said driving means; means for returning said actuating means; and means for automatically terminating each return movement of said actuating means at the same point irrespective of the extent of movement of said driving means.

15 43. The combination, with a platen; of a sheet-feeding mechanism for supplying work-sheets to said platen; driving means for rotating said platen varying amounts; a cam for actuating said sheet-feeding mechanism, operated from said driving means; a spring for returning said cam; and a stop for automatically terminating each return movement of said cam at the same point irrespective of the extent of movement of said driving means.

44. The combination, with a typewriting mechanism including a traveling carriage and type actions; of automatic actuators for operating said type actions; an actuator for controlling a traveling movement of said carriage; a master control set having a master member feeding to control successive actions of said actuators; means for interrupting the feeding movement of said master member during the said movement of said carriage; and an actuator coöordinate with, but separate from the other actuators, for automatically terminating said

carriage movement and continuing the feeding movement of said master member.

45. The combination, with a typewriting mechanism including a traveling carriage and type actions; of automatic actuators for operating said type actions; an actuator for starting the movement of said carriage in one direction; a master control set having a master member feeding to control successive actions of said actuators; means for interrupting the feeding movement of said master member when such movement of the carriage commences; and an actuator coöordinate with, but separate from the other actuators controlled from said carriage for automatically stopping the said movement thereof and concomitantly continuing the feeding movement of said master member.

46. The combination, with a typewriting mechanism including a traveling carriage and type actions; of automatic actuators for operating said type actions; an actuator for starting the return movement of said carriage; a master control set having a master member feeding to control successive actions of said actuators; means for interrupting the feeding movement of said master member when the return movement of said carriage commences; and an actuator coöordinate with, but separate from the other actuators controlled from said carriage for concomitantly stopping the return movement thereof and continuing the feeding movement of said master member.
